UNITED STATES PATENT OFFICE.

JOHN A. H. PARSONS, OF WHEELING, WEST VIRGINIA.

PHOTOGRAPHIC-PRINTING FRAME.

SPECIFICATION forming part of Letters Patent No. 309,736, dated December 23, 1884.

Application filed June 19, 1884. (No model.)

To all whom it may concern:

Be it known that I, JOHN A. H. PARSONS, a resident of Wheeling, in the county of Ohio and State of West Virginia, have invented 5 certain new and useful Improvements in Photographic-Printing Frames; and I do hereby declare that the following is a full, clear, and exact description of the invention, which will enable others skilled in the art to which 10 it appertains to make and use the same, reference being had to the accompanying drawings, and to letters of reference marked thereon, which form a part of this specification.

This invention relates to certain improvements in photographic-printing frames; and it has for its object to provide a vignetting attachment that may be readily attached to any frame and the parts adjusted so as to secure the proper vignetting result when exposed 20 for printing, as more fully hereinafter specified. This object I attain by the means illustrated in the accompanying drawings, in which—

Figure 1 represents a perspective view of 25 an ordinary printing-frame, showing my improved vignetting attachment applied thereto. Fig. 2 represents a longitudinal vertical section of the printing-frame and the vignetting attachment; and Fig. 3 represents a back view 30 of the printing-frame, showing a side view of the clamps by which the vignetting attachment is secured thereto.

The letter A indicates the printing-frame, which may be of the ordinary or any ap- 35 proved construction, and B indicates the vignetting-frame. The said vignetting-frame consists of a flat sheet of metal having up- turned edges B' on flanges at the sides and a central opening of rectangular or other shape, 40 as shown. The said vignetting-frame is se- cured to the printing-frame by means of the longitudinal clamping-plates C, which are preferably constructed of metal, having down- wardly-turned flanges D at their upper edges, 45 which set over the side flanges of the vignetting-frame and hold it to the face of the printing-frame, at the same time allowing the vignetting-frame to be adjusted longitudinally on the printing-frame. The vignetting-frame, 50 around its opening, is provided with a verti- cal rim, E, which is inclined from the lower

to the upper end, and over this rim is fitted a similarly-shaped hood, F, which is hinged at its lower or smaller end to the vignetting-frame contiguous to the lower or smaller end 55 of the rim E, whereby its angle may be varied with respect to the printing-frame and the negative from which the positive is to be printed. The upper plate or top of the hood has an opening, G, and the sides are provided 60 with springs H, secured to suitable supports, I, and having loosely-connected cross-bars K, which are adapted to hold the sheet on plate L upon the upper face or top of the hood in proper position. The said sheet or plate has 65 a central perforation or opening, M, for the transmission of light to the negative, and is provided with the usual translucent medium of ground glass, tissue-paper, or other suitable material for softening the light toward the 70 edges of the picture to produce the proper vignetting effect in the printed positive. The side clamps, which secure the vignetting-frame to the printing-frame, are provided with in- clined slots, by means of which they may be 75 secured to the printing-frame by the set-screws N, and at their ends are provided with bent- wire braces P, by which they are made to keep their form and securely hold the upturned edges of the vignetting-frame. 80

As constructed, it will be perceived that the vignetting-frame may be readily applied to any printing-frame and its angle readily ad- justed to suit the direction of the light, and that while the vignetting-frame may be ad- justed longitudinally to correspond to the pic- ture upon the negative the vignetting-plate may be adjusted in all directions, so as to pro- duce the proper vignetting effect around the print. 90

Having thus described my invention, what I claim, and desire to secure by Letters Patent, is—

1. The combination, with a photographic- printing frame, of the side clamps having ob- 95 lique slots and secured thereto by means of set-screws, and provided with downturned flanges at their upper edges adapted to hold a longitudinally-movable vignetting-plate, substantially as specified.

2. The combination, with the longitudinal clamping-plates, of the vignetting-plate with 100

flanged sides adapted to move longitudinally under the clamping- plates, substantially as specified.

3. The combination, with the vignetting-frame having an inclined rim, of the similarly-shaped hood hinged to the vignetting-frame, whereby the angle of said frame may be adjusted, substantially as specified.

4. The combination, with the vignetting-frame, of the springs extending from the cen-

ter to each end of the frame, and cross-wires whereby the vignetting-plate may be adjusted and held, substantially as specified.

In testimony that I claim the foregoing as my own I hereby affix my signature in presence of two witnesses.

J. A. H. PARSONS.
